UNITED STATES PATENT OFFICE

1,994,611

HAIR WAVER

Virgie F. Johnson, East Akron, Ohio

Application November 10, 1933, Serial No. 697,510

1 Claim. (Cl. 132—33)

The device forming the subject matter of this application is adapted to be used for imparting a wave to the human hair, in a way commonly understood by hairdressers and others.

5 The device comprises main and auxiliary members, preferably in the form of bars, the bars having lateral projections about which the hair is looped. The invention aims to provide novel means for separating the main and auxiliary members transversely, to tighten the hair and produce a satisfactory wave. A further object 10 of the invention is to provide novel means for guiding the main and auxiliary members as they are separated. A further object of the invention 15 is to provide a device of the class described which will possess great strength and be well adapted to withstand hard use.

It is within the province of the disclosure to improve generally and to enhance the utility of 20 devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, 30 without departing from the spirit of the invention.

In the accompanying drawing:

Fig. 1 shows in plan, a device constructed in accordance with the invention;

35 Fig. 2 is a longitudinal section;

Fig. 3 is an elevation wherein the device is viewed edgewise.

The device forming the subject matter of this application preferably is made of metal throughout. It comprises a main member 1, in the form of a bar, and an auxiliary member 2, likewise in the form of a bar, and the members 1 and 2 being located side by side. The member 2 is somewhat shorter than the member 1, so that one end 40 of the member 1 forms a handle 3. There are outwardly extended lateral projections 4 on the main member 1, and the auxiliary member 2 has corresponding projections 5, 5a and 5b. The projection 5a is an intermediate projection, and 45 is characterized by the fact that it is of less height than the projections 5. The projection 5b is a terminal projection and is characterized by the fact that it is of less height and of less diameter than the projections 5. The projections 4 are 50 disposed out of transverse alignment with re-

spect to the projections 5, 5a and 5b, that is, the projections on the respective sides of the implement are arranged in alternating order, longitudinally of the implement.

In the outer ends of the terminal projections 5 of the main member 1, recesses 6 are formed, and these recesses communicate with transverse bores 7, extended inwardly through the main member 1. The recesses 6 and the bores 7 cooperate to form shoulders 8, within the terminal 10 projections 4.

Transverse guides 9 are secured at 10, by riveting or otherwise, to the auxiliary member 2, and are slidable in the bores 7 of the terminal projections 4 of the main member 1. The guides 15 9 are supplied at their outer ends with enlarged heads 11, movable in the recesses 6, and adapted to cooperate with the shoulders 8, to limit the amount that the main and auxiliary members 1 and 2 are separated, by a means to be described 20 hereinafter. Owing to the fact that the guides or securing devices 9 are mounted in the terminal projections 4 of the main member 1, the connection between the members 1 and 2 is strengthened. The length of the guides 9 is such that the inner 25 edges 18 of the members 1 and 2 will come together before the heads 11 of the guides can emerge from the recesses 6. The heads 11, therefore, are at all times housed in the recesses 6, and they do not project outwardly, to catch the hair 30 which is being worked upon.

The members 1 and 2 are spaced apart transversely, at the will of an operator, by separating devices 12, 12a and 12b, such as screws, bearing at their inner ends against the inner edge of the 35 members 1. The separating device 12 is threaded into the inner end of the auxiliary member 2. The separating device 12a is threaded into the shorter projection 5a. The outer end surface of the head of the separating device 12a is in the 40 same plane with the outer end surfaces of the projections 5, and the diameter of the head of the separating device 12a is the same as the diameter of the projection 5. This is done to prevent the hair from catching on the head of the separating device 12a whilst the hair is being mounted in place, as indicated in Fig. 1. The separating device 12b is threaded into the projection 5b, and the diameter of the head of the separating device 45 12b is greater than the diameter of the projection 5b. The head of the separating device 12b, therefore, has some hold on the end portion of the wisp of hair and aids in keeping it in place, as Fig. 1 will indicate. The members 1 and 2 have 50 55

thinned ends 14, in which are located longitudinal seats or slots 15.

In practical operation, the screws 12, 12a and 12b are threaded outwardly in the auxiliary member 2, until the inner edges 18 of the members 1 and 2 can be brought into contact. The hair 16 is held on the outer ends of the members 1 and 2, against the projection 5b, by a binder 17, engaged in the seats or slots 15 of the ends 14 and is held on the member 2 by the laterally projecting head of the screw 12b. The hair 16 then is looped transversely about the projections 4, 5 and 5b, in opposite directions, substantially as shown in Fig. 1, and is drawn reasonably tight. The hair is wet or treated otherwise, and the members 1 and 2 are separated by threading the screws 12, 12a and 12b inwardly, to space the members 1 and 2, as shown in the drawing. By this operation, the hair is stretched tightly and a satisfactory wave is produced. As shown at 19, the members 1 and 2, and the projections 4, 5 and 5a are bevelled on their edges, where they come into contact with the hair 16. There are, therefore, no acutely sharp edges to cut or break the hair.

Having thus described the invention, what is claimed is:

In a hair waving device, main and auxiliary members located side by side, the main and auxiliary members having oppositely extended projections, certain of the projections on one of said members being of a common length, an intermediate projection on said one member being shorter than said certain projections, the outer terminal projection on said one member being shorter than said certain projections and of less diameter than said certain projections, and screws engaging the inner edge of the other of said members, one of the screws being threaded into the inner end of said one member independently of the projections thereon, another of the screws being threaded through the intermediate projection, longitudinally thereof, and having a head of approximately the same diameter as the outer end of the intermediate projection, the outer surface of the head being substantially flush with the outer end surfaces of said certain projections, and a third screw threaded through the terminal projection, longitudinally thereof, and having a head of greater diameter than the outer end of the terminal projection, to afford a hair-hold.

VIRGIE F. JOHNSON.
